UNITED STATES PATENT OFFICE.

JOHN ROMSHE, OF CINCINNATI, OHIO.

DISPLAY-RACK.

933,851.

Specification of Letters Patent. Patented Sept. 14, 1909.

Application filed January 9, 1909. Serial No. 471,469.

To all whom it may concern:

Be it known that I, JOHN ROMSHE, a citizen of the United States, residing at Cincinnati, in the county of Hamilton and State of 5 Ohio, have invented a new and useful Improvement in Display-Racks, of which the following is a specification.

This invention relates to a display rack designed for holding and displaying such 10 articles as post cards, cigars, cigarettes, and other small articles.

An especial object of the invention is a show case which will occupy a comparatively small floor space which can be moved 15 from one part of a room to another, which revolves upon its movable support, and which can be opened out thus displaying the goods carried by it successively and in a horizontal position.

20 The invention consists of the novel features of construction hereinafter described, pointed out in the claims and shown in the accompanying drawings, in which,

Figure 1 is a front elevation of the case. 25 Fig. 2 is a section on the line 2—2 of Fig. 1. Fig. 3 is a section upon the same line, the casing being shown in open position. Fig. 4 is a section on the line 4—4 of Fig. 3.

In these drawings, 1 represents a suitable 30 base mounted upon casters, and upon which is revolvably mounted a supporting bracket 2 upon which bracket is firmly secured a suitable oblong base 3. The front and rear edges of this base are oppositely beveled as 35 shown in the drawings and upon the base is mounted an upwardly and rearwardly inclined rectangular casing 4. The front of this casing is open and is provided with a glass cover 5 permanently secured in position. Within the casing and immediately 40 to the rear of the glass cover 5 is placed an inclined back 6 designed to display upon its front face samples of the cards or other merchandise, which samples are visible through 45 the glass front 5.

On the base 3 are transversely arranged 50 parallel rack bars 7 the projections upon which have the same inclination as the glass front 5. Resting upon these rack bars and held in place by the projections upon them are a plurality of boards 8 which are held in

place at the top by suitable locking means, such as spring pressed bolts 9 which engage suitable notches 9^a formed in the top of the casing. It will be obvious that any simple 55 and convenient form of catch may be employed.

A back 10 is hinged to the rear edge of the base 3 and carries a stop or brace bar 11 beveled to coöperate with the rear edge of 60 the base, and limiting the downward movement of the back 10, holding the same in horizontal position as shown in Fig. 3. A suitable fastening member 12 serves to lock the back in closed position. 65

Any suitable means such as wire or metal clips 13 are carried by the back and various members or leaves for the purpose of holding articles in place upon said leaves, and it will be obvious that the style of securing the 70 device employed will depend upon the nature of the article to be held, a clip which would be suitable for post cards not being sufficient to hold cigar boxes in place. It will also be obvious that the case can be made in many 75 different sizes and the space between the various leaves would vary with the nature of goods to be held, and it will also be obvious that any convenient number of leaves 80 may be employed, depending upon the depth of the casing, and the size of the articles to be shown. The casing may be also either plain or of any ornamental design, according to the taste of the purchaser. 85

What I claim is:—

1. A device of the kind described comprising a pedestal a revolving bracket carried thereby, a casing supported by said bracket, said casing inclining upwardly and rearwardly a glass front for said casing, a 90 hinged back, means for limiting open movement of the back, a plurality of removable leaves held in said casing between the front and the back, and means for holding said leaves in place. 95

2. A device of the kind described comprising a movable pedestal, a bracket rotating upon said pedestal, an oblong base carried by said bracket, said base having front and rear edges beveled, an upwardly and rearwardly inclined casing supported by said base, a transparent front carried by the cas- 100

ing, a back hinged to said base, a beveled brace carried by the back and coöperating with the rear edge of the case to form a stop for the base, rack bars carried by the base, 5 and a plurality of leaves resting upon said rack bars, means for locking the upper edges of said leaves in position, and means carried

by said leaves for holding articles of merchandise.

JOHN ROMSHE.
